UNITED STATES PATENT OFFICE.

JOHN M. HESS, OF GRUNDY CENTER, IOWA.

FERTILIZER-DISTRIBUTER.

No. 813,556.

Specification of Letters Patent.

Patented Feb. 27, 1906.

Application filed July 25, 1904. Serial No. 217,952.

To all whom it may concern:

Be it known that I, JOHN M. HESS, a citizen of the United States of America, and a resident of Grundy Center, Grundy county, 5 Iowa, have invented a new and useful Fertilizer-Distributer, of which the following is a specification.

The object of this invention is to provide improved means for distributing fertilizer 10 over the surface of the ground.

My invention consists in the construction, arrangement, and combination of the elements hereinafter set forth, pointed out in my claims, and illustrated by the accompanying drawings, in which—

Figure 1 is a plan or top view of the machine, a portion of the tongue being broken away. Fig. 2 is a bottom view of the machine, a portion of the tongue being broken 20 away. Fig. 3 is an elevation of one side of the machine. Fig. 4 is an elevation of the opposite side of the machine. Fig. 5 is an elevation of the front of the machine. Fig. 6 is an elevation of the rear of the machine. Fig. 25 7 is a longitudinal section of the machine on line 7 7, Fig. 2, the trucks and other parts being omitted for clearness. Fig. 8 is a detail view of part of the mechanism. Fig. 9 is a detail view of the hand-operated lever devices for controlling the primary clutches.

In the construction of the machine as shown a bed-frame is provided and is composed of side bars 10 11, a front bolster 12, fixed to and beneath the forward end portions of said side bars, and cross-bars 13, 14, 15, and 16, fixed to said side bars intermediate of their ends. The bolster 12 is further secured to the side bars 10 11 by braces 17 18, extending rearwardly and upwardly from 35 the end portions of said bolster. A circular plate 19 is mounted on the central portion of the lower face of the bolster 12 and fixed thereto and is further secured to said bolster by an arched strap 20, crossing said ring diametrically and extending over the center of the bolster. Another metal ring 21 is provided and is mounted on and fixed to the central portion of the front axletree 22. The ring 21 is further secured by an arched strap 40 45 23 across said ring diametrically and extending beneath the central portion of the axletree 22. Registering apertures are formed in the bolster 12, strap 20, axletree 22, and strap 23, and a king-bolt 24 is mounted 50 55 through said apertures and is provided with a head on one end and a nut on the other end,

whereby it is firmly seated and retained in place and serves as a pivotal connection for the axletree and bolster. The rings 19 21 and straps 20 23 constitute a fifth-wheel 60 whereby the axletree may be connected to the bolster by the king-bolt. A plurality of eyebolts 25—in this instance four in number—are mounted horizontally through the axletree 22, and a rod 26 is mounted rigidly 65 yet detachably through the eyes of said bolts in front of said axletree. A tongue or pole 27 is provided and is constructed with plates 28 on opposite sides of its rear end portion and braces or hounds 29, fixed to and diverging 70 from its rear end portion, and said plates and hounds are apertured at their rear ends and are pivoted by means of said apertures on the rod 26, the hounds confined by contact with the inner surfaces of the outer eyebolts and 75 the plates confined by contact with the inner surfaces of the inner eyebolts. An axle 30 is mounted on the lower face of the axletree 12 and is secured thereto by hook-bolts 31 near its end portions and by the king-bolt 24, extending 80 through its center. Spindles of usual form are constructed on or attached to end portions of the axle 30, and supporting-wheels 32 33 are revolvably mounted thereon and support the forward end portion of the machine. 85

Journal-bearings 34 35 and 36 37 are mounted on, fixed to, and arched downwardly from side bars 10 11, and the cross-bars 14 15 of the bed-frame and the seats or bearings thereof are in alinement across the machine. 90 An axle member 38 is mounted for rotation in the journal-bearings 34 35, and an axle member 39 is mounted for rotation in the journal-bearings 36 37 in alinement with the axle member 38. Collars 40 41 are mounted 95 on and fixed to the axle members 38 39, respectively, adjacent the inner faces of the journal-bearings 34 37 and serve to limit longitudinal movement of said axle members. Supporting traction-wheels 42 43 are mounted 100 rigidly on the outer end portions of the axle members 38 39, respectively, and support the rear end portion of the machine as well as provide the motive power for the mechanism hereinafter described. The inner end portions of the axle members 38 39 abut each other in the median line of the machine within the hub of a gear-wheel 44, but are not connected with each other or with 105 said gear-wheel directly. Clutch members 110 are formed on opposite end portions of the hub of the gear-wheel 44, and clutch mem-

bers 45 46 are mounted on and feathered for sliding movement relative to the inner end portions of the axle members 38 39 and are held normally in engagement with the clutch members on the hub of the wheel 44 by expansive coil-springs 47 48, interposed between them and the journal-bearings 35 36. It is the function of the clutch members 45 46, either separately or conjunctively, to transmit rotary motion of the axle members 38 39 to the gear-wheel 44 for the purpose of driving mechanism hereinafter described at times, and provision is made for holding said clutch members out of engagement, as follows: Yoke-arms 49 50 are pivoted at their forward end portions on a bolt 51, seated in the central portion of the cross-bar 13. Yokes are formed on the rear end portions of the arms 49 50 and engage in annular grooves in the clutch members 45 46. Toggle-levers 52 53 are pivoted at their outer ends to the centers of the yoke-arms 49 50, and at their inner ends said toggle-levers are conjunctively pivoted to the rear end portion of an actuating-bar 54. The actuating-bar 54 extends forward within the bed-frame from its point of attachment to the toggle-levers to a point beneath a foot-board 55, fixed to and projecting forward from said bed-frame. A crank-shaft 56 is journaled in bearings 57, fixed to the lower end portion of the foot-board 55, and is provided with a crank 58 on one end portion, which crank is outturned at its extremity and extends through a slot 59 in the forward end portion of the draft-bar 54 and is secured by a nut 60. A lever-arm 61 on the crank-shaft 56 extends through a slot 62 in the foot-board 55 and is adapted for manual actuation to move the draft-bar 54 in either direction positively. The ordinary function of the lever-arm 61 is to manipulate the clutch members 45 46 into engagement with the clutch on the hub of the gear-wheel 44, and when so engaged said lever-arm is retained by contact with a hook 63 on a bell-crank lever 64, fulcrumed on a seat-bar 65, which seat-bar crosses and is fixed to the top of the forward ends of side boards, hereinafter described. A retractile coil-spring 66 is fixed to the bolster 12 and to the crank 58 and tends to move the draft-bar 54 rearward and disengage the clutch members 45 46 from the hub of the wheel 44. An angle-iron 67 is fixed to the forward edge of the seat-bar 65 and tends to hold the handle-lever 61 against lateral movement out of the hook 63.

Journal-bearings 68 69 are mounted on the cross-bars 15 16 and the side bar 11, respectively, of the bed-frame, and a counter-shaft 70 is mounted for rotation in said journal-bearings and projects at one end outside said bed-frame. A pinion 71 is mounted rigidly on the counter-shaft 70 between its journal-bearings and meshes with the gear-wheel 44,

and collars 72 limit and prevent longitudinal movement of said counter-shaft.

Track-bars 73 74 are mounted on and spaced apart from the inner surfaces of the side bars 10 11 of the bed-frame, and rollers 75 are arranged in series in the space between said track-bars and side bars and project above the upper margin of the track-bars. It is the function of the rollers 75 to form a frictionless bed and support for the fertilizer-apron 75 about to be described. The fertilizer-apron is formed of an angular head-piece 76, which head-piece has a bottom and front plate rigidly connected and secured together by braces 77 and slats 78, arranged parallel to each other and parallel to the head-piece and suitably connected. I have illustrated cables 79 80, arranged parallel with each other, fixed at their forward ends to the head-piece 76, crossing beneath said head-piece and the end portions of the intermediate slats 78, and fixed rigidly at their rear end portions to the rearmost slat, (indicated by the numeral 81.) Intermediate of its ends each cable 79 80 is secured to the slats and head-piece by hook-bolts 82, extending through said slats or head-piece, embracing the cables in their hooks, and secured at their upper ends by nuts 83, engaging the upper surfaces of the slats or head-piece. Through the employment of the cables constructed as described to connect the head-piece and various slats I am enabled to produce an apron which may be flexed repeatedly and at the same time provide maximum strength in resisting draft and jerks in the operation of the machine.

Side boards 84 85 are mounted on, fixed to, and rise from the side bars 10 11 of the bed-frame. The rear end portions of the side boards 84 85 are bifurcated, and yoke-bars 86 87 are mounted across the bifurcations thereof. The yoke-bars 86 87 are of identical construction, and each consists of circular yokes formed with alining stems extending in opposite directions, the upper stem 110 confined by an angle-plate 88 on the upper portion of a side board and the lower stem extending through the rear end portion of the side bars 10 11 and arranged for vertical adjustment by means of nuts 89 90 above 115 and below said side bars. Adjusting-screws 91 92 are mounted radially of the circular yokes and are adapted to engage, center, and support journal-bearings 93 94 within said yokes. A rake-shaft 95 is mounted for rotation in the journal-bearings 93 94, and circular rake-heads 96 97 are mounted rigidly on said shaft and are connected by and support rake-bars 98, which rake-bars extend across the machine and are provided with 120 rake-teeth 99, arranged in staggered relations thereon.

A sprocket-wheel 100 on the shaft 70 is connected by a sprocket-chain 101 to a sprocket-wheel 102 on one end portion of the 130

rake-shaft 95. A drum-shaft 103 is journaled in bearings at the rear end portions of side bars 10 11, and a drum 104 is mounted loosely thereon between said bearings. A 5 clutch member is formed on one end portion of the drum 104 and mates at times with a clutch member 105, feathered on the shaft 103. A cable 106 is fixed at one end to the drum 104 and is adapted to be wound thereon, and the opposite end of said cable is fixed to the lower face of the central portion of the head-piece 76. A bell-crank lever 107 is fulcrumed on the upper face of the cross-bar 16, and the shorter arm of said lever engages in 10 an annular groove in the clutch member 105. The longer arm of the bell-crank lever 107 is connected by a rod 108 to one end of a pedal-lever 109, which pedal-lever is mounted through the slot in the foot-board 55 and is 15 journaled for pedal oscillation. A retractile coil-spring 110 connects the free end of the bell-crank lever 107 to the cross-bar 15 and applies a strain to said lever, which tends to holds the clutch member 105 in engagement 20 with the clutch member of the drum 104. A lug 111 is mounted on the forward face of the cross-bar 16 and tends to limit and determine oscillation of the bell-crank lever 107 in opposition to the resilience of the spring 110. 25

30 A drum-shaft 112 is mounted for rotation in bearings fixed to the forward end portions of the side bars 10 11 of the bed-frame. A cable 113 is fixed at one end to and normally is wound on a drum 114, fixed to the drum-shaft 112, and the opposite end portion of said cable is fixed to the central portion of the bottom of the head-piece 76. This cable 113 is shown in Fig. 7. A cable 115 is fixed at one end to the rearmost slat 81 of the fertilizer-appr'n and extends forward beneath the machine and is fixed to the drum 114 and is adapted to be wound on said drum oppositely to the cable 113. A skeleton casing or frame 116 is fixed to and depends from the cross-bars 14 16 or the journal-bearings attached thereto and protects the gear-wheel 44 and pinion 71 from the entangling engagement with the cable 115. Cables 117 118 are fixed at their forward ends to the drum-shaft 112 and are adapted to be wound on 35 said drum-shaft oppositely to the cable 113. The rear end portions of the cables 117 118 are attached to the forward end portions of retractile coil-springs 119 120, and the rear end portions of said springs are attached to 40 end portions of the cross-bar 16 of the frame. 45

50 A sleeve 121 is feathered on one end portion of the rake-shaft 95, and a friction-wheel 122 or brush-wheel is mounted rigidly on said sleeve. A bell-crank lever 123 is fulcrumed on a bracket 124, fixed to the side board 84 and is formed with a yoke on its rear end, engaging in an annular groove in the sleeve 121. The shorter arm of the bell- 55 crank lever 123 is connected by a rod 124^a to

a hand-lever 125, pivoted on the forward end portion of the side board 84. A segmental rack 126 is fixed to the side board 84, and a detent 127, slidingly mounted on the lever 125, engages said rack. The detent 127 is provided with integral wings 128 129, leading in opposite directions therefrom and folded around and slidingly engaging the lever 125, and the upper end portion of the detent extends through an ear 130 on the lever and is 60 provided with an eye connected by a rod 131 to a tripping-lever 132, mounted on the upper end portion of the hand-lever and adapted for manual compression thereto. An expansive coil-spring 133 is interposed between the wings 65 on the detent 127 and the ear 130 and surrounds the upper portion of the detent and tends to depress the detent normally into engagement with the rack 126. It is the function of the hand-lever 132 to oscillate the bell-crank lever 123 and move the sleeve 121 and brush-wheel 122 longitudinally of the shaft 95. A bracket 134 is mounted on and projects laterally from the rear end portion of the side board 84, and a counter-shaft 135 is mounted 70 for rotation in a journal-bearing on said bracket. A disk 136 is mounted rigidly on one end portion of the counter-shaft at right angles to the brush-wheel 122, and the upper surface of said disk is adapted to be engaged by 75 said brush-wheel. Any adjustment of the brush-wheel longitudinally of the shaft 95 moves said brush-wheel radially of the disk 136 and changes the speed at which said disk is rotated by the brush-wheel. A bevel-gear 137 is mounted rigidly on the lower end portion 80 of the counter-shaft 135 and meshes with a bevel-gear 138, rigidly mounted on a stub-axle 139, seated in a rear end portion of the side bar 10 of the bed-frame. A socket 140 is mounted on the outer end portion of the stub-axle 139 and receives the lower end portion 85 of the counter-shaft 135, and an expansive coil-spring 141 is mounted on said counter-shaft and impinges said socket and the bevel-gear 137, respectively. Thus is provision made for longitudinal movement of the counter-shaft 135 to compensate for vertical adjustment of the rake-shaft 95 or for wear of the brush-wheel and disk, at the same 90 time insuring a yielding pressure of the disk against the brush-wheel. This movement of shaft 139, however, is not sufficient to remove the gears 137 and 138 from mesh. A pinion 142 is rigidly attached to the shaft of the bevel-gear 138 and meshes with a pinion 143 of materially greater diameter than the gear, which pinion is mounted rigidly on the drum-shaft 103. 95

100 A bell-crank lever 144 is fulcrumed on the lower face of the cross-bar 13, and one arm of said lever is connected by a rod 145 to the extremity of the longer arm of the bell-crank lever 64. A retractile coil-spring 146 is connected at one end to the lower margin of the 105

110

115

120

125

130

side bar 11 and at its other end to the bell-crank lever 144, and the strain of said spring tends to hold the lever 64 in such position that the hook 63 thereon will engage and retain 5 the hand-lever 61. A rod 147 is slidingly mounted in a bearing 148 on the cross-bar 15, and the forward end of said rod is connected to one arm of the bell-crank lever 144. A hook is formed on the rear end portion of the 10 rod 147 and projects upward across the rear margin of the cross-bar 15 and into the path of travel of a loop 149, fixed to and projecting downwardly from the lower face of the head-piece 76.

15 Brackets 150 151 are fixed to and project above the forward portions of the side boards 84 85, and arms 152 153 are pivoted in the upper ends of said brackets and project rearwardly and downwardly therefrom to points 20 of attachment to opposite end portions of a clearer-bar 154. The arms 152 153 are formed with lugs 155 156, projecting outward therefrom and engaging the upper margins of the side boards 84 85. Retractable 25 coil-springs 157 158 further connect the arms 152 153 to the brackets 150 151 and tend to hold the lugs on said arms in contact with the upper margins of the side boards. The clearer-head 154 is provided with teeth 159, 30 projecting rearwardly and downwardly into spaces between the teeth 99 on the rake-bars 98 and just out of contact with said rake-bars.

In practical operation of this machine the 35 parts are assembled as shown in the drawings and above described, except that the brush-wheel 122 may be positioned or adjusted wherever desired relative to the disk 136. The machine then is moved across the 40 field with the apron loaded with fertilizer. The traction-wheels 42 43 transmit rotary motion through the clutch members 45 46 to the gear-wheel 44, and said gear-wheel in turn rotates the pinion 71, counter-shaft 70, 45 and sprocket-wheel 100. The sprocket-wheel 100, acting through the chain 101, rotates the sprocket-wheel 102 and rake-shaft 95, thus revolving the rake in the direction of the arrow in Fig. 4. In the rotation of the 50 rake-shaft 95 the brush-wheel 122 engages and rotates the disk 136, counter-shaft 135, and bevel-gear 137, and the motion of the bevel-gear is transmitted, through the bevel-gear 138, to the spur-gear 142. The spur-gear 142 rotates the pinion 143 and drum-shaft 103, and since the clutch member 105 is in engagement with the drum 104 such rotation of the drum-shaft rotates the drum and winds the cable 106 thereon. Since the 55 cable 106 is attached to the head-piece 76 of the apron, it follows that the winding of said cable on the drum 104 draws said apron rearward. The rearward movement of the apron effects an unwinding of the cable 113 from the drum 114, and such unwinding effects a

rotation of said drum 114 and winds the cables 117 118 on the shaft 112 and stretches the springs 119 120 to the end of storing power in said springs. The rearward movement of the apron also causes the cable 115 70 to travel forwardly around the drum 114 and in so doing insure the forward movement of the tail end of the apron beneath the bed-frame and sustains or supports said tail end of the apron clear of the ground. When the 75 apron has reached its rearmost limit of movement, the loop 149 on the head-piece 76 engages the hook on the rod 147 and moves said rod rearward a distance sufficient to oscillate the bell-crank levers 144 and 64 and release the 80 hand-lever 61 from the hook 63, whereupon said hand-lever moves forward under strain of the spring 66 and effects an operation of the yoke-arms 49 50 sufficient to disengage the clutch members 45 46 from the gear-wheel 44 and prevent further operation of the mechanism by cutting off the supply of traction-power therefrom. Further forward movement of the machine has no effect whatever on the mechanism which moves the rake 90 and apron. Since the rake rotates in the direction of the arrow in Fig. 4, it has a tendency to impede the delivery of fertilizer by the apron beneath the rake, the teeth 99 moving the fertilizer back and insuring the delivery 95 of a thin and uniform sheet of fertilizer in more or less pulverized condition from the apron. It sometimes occurs that portions of the fertilizer will adhere to rake-bars 98 and teeth 99, and to clear said teeth the 100 clearer-head 154 and teeth 159 are provided, yieldingly mounted, as described, and adapted to comb the rake and clear a maximum amount of substance therefrom. The yielding mounting of the clearer-bar 154 avoids 105 breaking the teeth or arms thereof or the teeth of the rake when a superior resistance is met with, such as frozen fertilizer or mineral chunks carried by the rake. When the apron has been unloaded through the operation 110 above described, foot-power may be applied to depress the pedal 109 and apply draft to the rod 108 sufficient to move the bell-crank lever 107 against the resilience of the spring 110 and disengage the clutch 105 115 from the drum 104, whereupon the resilience of the springs 119 120 unwinds the cables 117 118 from the drum-shaft 112 and in so doing rotates said drum-shaft and the drum 114 and rewinds the cable 113 on said 120 drum. The rewinding of the cable 113 on the drum 114 draws the apron into the initial position shown in the drawings and first described, the cable 115 traveling rearward around the drum and at all times sustaining 125 the tail end of the apron clear of the ground.

I claim as my invention—

1. A fertilizer-distributer comprising a traction-truck, a rake driven by said truck, an apron driven by said rake in one direction, 130

- yielding pressure devices for returning the apron to its initial position and mechanism operated by the apron, to suspend the operation of its driving mechanism.
5. 2. A fertilizer-distributer comprising a traction-truck, a revolving rake, driving connections between said truck and rake, manually-operated devices for establishing said driving connections, automatically-operated devices for suspending said driving connections, an apron driven in one direction by said rake, and yielding pressure devices for returning said apron to its initial position.
15. 3. A fertilizer-distributer comprising a traction-truck, a revolving rake, suspendable driving connections between the truck and rake, an apron mounted for travel beneath said rake, suspendable driving connections between the apron and rake, and means exerting a yielding pressure upon the apron to retard its movement from and automatically return it to its normal position.
25. 4. A fertilizer-distributer comprising a traction-truck, a revolving rake, suspendable driving connections between said traction-truck and rake, an apron mounted for travel beneath said rake, friction-gearing connecting said rake and apron, means for suspending travel of the apron independently of the movement of the rake, and springs for reversing the travel of the apron to return it to its normal position.
35. 5. A fertilizer-distributer, comprising a traction-truck, a revolving rake, driving connections between said truck and rake, manually-operated devices for establishing said driving connections, automatically-operated devices for suspending said driving connections, an apron mounted for travel beneath said rake, driving connections between said rake and apron, pedally-operated releasing mechanism for suspending the driving connections between the rake and apron, and yielding pressure devices for returning said apron to its initial position.
45. 6. A fertilizer-distributer comprising a traction-truck, a rake, driving connections between the truck and rake, manually-operated devices for establishing said connections, means for automatically suspending said connections, an apron movably mounted beneath the rake, driving connections between the rake and one end of the apron, and a spring for automatically returning the apron to its initial position.
55. 7. In a machine of the class described, an apron, a drum-shaft mounted for rotation beneath the rear end of said apron, a drum loosely mounted on said shaft, a cable connected to the forward end of said apron and adapted to be wound on said drum and clutch connections between said drum-shaft and drum.
65. 8. In a machine of the class described, an apron, a drum-shaft mounted for rotation beneath the rear end of said apron, a drum on said shaft, a cable attached at one end to the forward end of said apron and adapted to be wound on said drum, another drum-shaft, a cable attached to the forward end of said apron and adapted to be wound on the second drum-shaft, and spring-resisted cables adapted to be wound on the second drum-shaft in opposition to the second cable.
75. 9. In a machine of the class described, an apron, drum-shafts at either end of said apron, cables attached to the forward end of the apron and adapted to be wound on said drum-shafts oppositely, spring-returning cables adapted to be wound on one drum-shaft in opposition to the other cable wound thereon, and a cable sustaining the tail end of said apron at times.
85. 10. In a machine of the class described, an apron, means for driving said apron in one direction, springs for returning said apron to its initial position and mechanism, operated by the apron, to suspend the driving mechanism.
90. 11. In a machine of the class described, an apron, mechanism for driving said apron in one direction, springs for returning said apron to its initial position, and pedal-operated mechanism for suspending the driving mechanism and establishing the spring-returning function.
100. 12. In manure-spreader, the combination of a main driving-shaft, a beater, a series of gears adapted to connect said main shaft with said beater, a conveyer, a second series of gears for connecting said beater to said conveyer, means for moving said connecting-gears, a spring adapted to be put under tension when said first-mentioned gears are thrown into mesh with the beater a holding device for holding same connected, and means connected with said conveyer for releasing said spring, for the purpose specified.
105. 13. A fertilizer-distributer comprising a traction-truck, a revolving rake, suspendable connections between said truck and rake, an apron mounted for travel beneath, and operated in one direction by, said rake, yielding pressure devices for returning the apron to its initial position, a drum-shaft beneath said apron, gear connections between said rake and drum-shaft, and clutch mechanism on said drum-shaft for suspending the movement of the apron independent of the movement of the rake.
115. 14. A fertilizer-distributer comprising a frame, journal-bearings on said frame, axle members mounted in said journal-bearings, traction-wheels supporting said axle members, a rake mounted on said frame, gear connections between said rake and axle members, clutch mechanism between said gear connections and axle members, an apron mounted for travel beneath, and adapted to be moved in one direction by, the rake, yield-

6
ing pressure devices for returning the apron to its initial position, and a steering-truck carrying the forward end of said frame.

15. In a machine of the character described, 5 traction mechanism, a counter-shaft, suspendable connections between the traction mechanism and counter - shaft, a rake, sprocket-and-chain connections between said counter-shaft and rake, an apron beneath,

and adapted to be moved in one direction by, to the rake, and yielding pressure devices for returning the apron to its initial position.

Signed by me at Grundy Center, Iowa, this 23d day of April, 1904.

JOHN M. HESS.
